SURGICAL DRILL

Francisco Elias de Godoy Moreira, Sao Paulo,
Brazil

Application November 5, 1938, Serial No. 239,046

6 Claims. (Cl. 128—83)

My invention relates to a surgical drill apparatus and more particularly to an attachment for an electric motor designed to drill a channel through the parts of a fractured bone in order to permit or facilitate the entry of a bone-screw therethrough.

In my application filed November 2, 1938, I described a bone-screw having at least two different diameters along its length and I illustrated the entry of said bone-screw into a channel previously drilled for that purpose.

A bone-screw is of particular advantage in the fracture of the femur or hip bone and it is usually applied at the base of the trochanter, through the center of the neck of the femur and anchored in the ball or head thereof.

It is essential that a channel to receive the bone-screw be first drilled through the bone and to insure against any deviation of the drill from its prescribed course, a guide or "Kirschner" wire is caused to enter the said parts in a manner well known to the art. The "Kirschner" wire having been properly inserted, a drill having a longitudinal bore is applied thereover and the channel is duly drilled.

Bearing the foregoing in mind, it is an object of my invention to provide a drill which may be actuated by an electric motor and which is designed to drill the channel to conform to the shape of the bone-screw to be subsequently lodged therein.

Another object of my invention is to provide means in combination with such a drill whereby the degree of penetration of said drill into the bone may be easily ascertained.

Another object of my invention is to provide means in combination with such a drill to insure against the rotation of the "Kirschner" wire while the drill is rotating around it.

Another object of my invention is to provide an electric motor attachment for such a drill which shall simplify and facilitate the procedure above outlined by affording the operator improved visual access to the site of entry of the drill.

Other objects of my invention will be obvious from the following description it being understood that the above general statements of the objects of my invention are intended to explain and not to limit it in any manner.

Fig. 1 is a top view, partly in section of my apparatus, the bone operated upon being shown in dotted lines.

Fig. 2 is a section on the line 2—2 of Fig. 1.

Fig. 3 is a longitudinal section through part of the drill.

Fig. 4 is a section on the line 4—4 of Fig. 1. Fig. 5 is a section on the line 5—5 of Fig. 1.

Fig. 6 is a section on the line 6—6 of Fig. 1.

Referring to the drawing, M represents an electric motor which is preferably portable, being directly connected to the drill in the preferred embodiment.

The action of the motor shaft S is translated into perpendicular motion by the endless screw and worm gear mechanism W, which mechanism is located in the housing 10 and the worm gear thereof is integral with the jack-shaft 11.

A pin 12 cooperates with the bayonet slot 13 to connect the drill D to the jack-shaft 11. The drill D is formed with two types of drill-bits 14 and 15, the drill-bit 14 operating to create a channel section of less diameter than the drill-bit 15. Slidably mounted on the drill D is the nut 16, provided with a set-screw 17 by which it is fixed to the drill D. The function of the nut 16 is to limit the entrance of the drill into the bone and the set-screw 17 together with suitable indicia on the periphery of the drill D is operative to adjust the effective length of the drill.

The opposite side of casing 10 is formed with a wall 18 which wall has the lugs 19 and 20 set thereon in any suitable manner as by screwing or riveting. The casing 10 may generally be designated as an elbow shaped housing of which one arm is connected to and is in alignment with the motor shaft while the other arm is perpendicular thereto and supports the drill.

Detachably secured to the wall 18, is the tubular member 21, which by means of its wall 22 and slots 23 and 24, may be secured to the wall 18 by receiving the lugs 19 and 20 in the apexes of slots 23 and 24. The tubular member 21 is hollow and is provided with an end nut 25, having a shank 26, which end nut and shank operate as a wall and peg for the coil spring 27 in the tubular member 21. The spring 27 is retained in the tubular member by the post 28, which is provided with a slotted head, and a pin 29 which is adapted for movement in the slot 30 formed in the tubular member 21. Pressure on the post 28 is therefor effective to depress the spring 27, the pin 29 riding in the slot 30.

It will be noted that the drill D, the jack-shaft 11, the worm gear of mechanism W, the wall 18, and the wall 22 are all formed with a central internal bore to receive the "Kirschner" or guide wire K.

My invention is practiced in the following manner:

After anesthesia and the incision having been

made in the body of the patient being operated upon the femur is exposed, the fracture having previously been reduced by suitable means well known in the art.

After determining the site that the bone-screw will occupy depending on the location of fracture and other facts which are known to the surgeon, the guide wire K is introduced thereat and inserted into the shaft, through the center of the neck and into the ball or head of the femur. This practice is standard and requires no explanation of its procedure. When the guide wire K has been thus inserted it should be tapped with a mallet so as to firmly lodge it in the spongy bone of the head of the femur.

The nut 16 having been adjusted, the drill D is applied over the guide wire K and the channel through the bone is drilled. The further end of the channel will be of less diameter than the nearer end due to the drill-bits 14 and 15. This result is required so that the channel is shaped according to the particular parts of the bone-screw which will thereafter occupy it, the section drilled by the drill-bit 14, being equivalent to the diameter of the shank of the drive-screw 25 thread portion of the bone-screw.

My apparatus may be used without the tubular member 21. In this manner, the guide wire K extends through the drill D, the jack-shaft 11, the casing 10, the worm gear of mechanism W, 30 and the wall 18, protruding through the outer end of said wall which is provided with an axial bore. As the drill progresses through the bone, more of the guide wire K protrudes through the wall 18 and the extent of penetration may be ascertained. In addition, it is most essential that action of the drill is not transmitted to the guide wire since said guide wire should not rotate during this process. It is obvious that should this occur the guide wire might traverse 35 entirely the head of the femur, and, puncturing its wall, would probably prove fatal to the patient. Therefore, through my apparatus, the guide wire is exposed so that any rotation can be immediately detected, as well as the degree 40 of penetration ascertained.

The tubular member 21 is of assistance in effecting the above results in an improved manner by preventing such rotation. When it is secured to the wall 18 as hereinabove described, the guide wire K can be firmly retained in the slotted head of post 28 which cannot rotate due to the pin 29 in slot 30. Thus the guide wire K is positively retained against rotation, it is visible through the slot 30 so that the degree of penetration of the drill D is ascertained and furthermore, the guide wire K is prevented from dislodging itself from the head of the femur by the pressure of the post 28. As the drill advances in the bone, the coil spring 27 recedes and permits the free longitudinal movement of the guide wire K against the action of said coil spring.

I have shown a preferred embodiment of my invention but it is obvious that numerous changes and omissions may be made without departing from its spirit.

I claim:

1. The combination with a guide wire of a

drill attachment for a motor comprising an elbow shaped housing having power transmission mechanism in one arm thereof, driven mechanism located within the other arm thereof, a 5 drill operatively connected to said driven mechanism, said drill, driven mechanism and other arm being formed with an axial bore for the reception of said guide wire therethrough and gripping means secured to said housing in alignment with said axial bore for engaging and preventing the rotation of said guide wire while said drill is being driven.

2. The combination with a guide wire of a drill attachment for a motor comprising an elbow shaped housing, having power transmission mechanism in one arm thereof, driven mechanism within the other arm thereof, a drill operatively connected to said driven mechanism, a tubular member secured to said other arm of said housing, spring means within said tubular member, said drill, driven mechanism, other arm and tubular member being formed with an axial bore for the reception of said guide wire therethrough, said guide wire bearing against said spring means against the action of said spring, means, whereby said guide wire is inwardly urged by said spring means.

3. An attachment according to claim 2, wherein said tubular member includes means to prevent rotation of said guide wire.

4. The combination with a guide wire of a drill attachment for a motor comprising an elbow shaped housing having power transmission mechanism in one arm thereof, driven mechanism located within the other arm thereof, a drill operatively connected to said driven mechanism, a tubular member secured to said other arm of said housing in alignment with said drill, said drill, driven mechanism, other arm and tubular member being formed with an axial bore for the reception of said guide wire therethrough, spring means located within said tubular member whereby said guide wire may bear against said spring means, and means within said tubular member to prevent rotation of said guide wire, said tubular member having a slot formed in the wall thereof whereby the degree of penetration of said guide wire within said tubular member may be ascertained.

5. The combination with a guide wire of a drill attachment for a motor comprising an elbow shaped housing having power transmission mechanism in one arm thereof, driven mechanism located within the other arm thereof, a drill operatively connected to said driven mechanism, said drill, driven mechanism, and other arm being formed with an axial bore for the reception of said guide wire therethrough and combined means secured to said housing for preventing rotation of said guide wire and for urging said guide wire inwardly to prevent its outward displacement.

6. A device according to claim 5 wherein said means comprises a head for engaging the free end of said guide wire, a support for said head to prevent the rotation thereof and a spring actuating said head inwardly.

FRANCISCO ELIAS DE GODOY MOREIRA.
